CLAIM

The ornamental design for a paper or towel dispenser, as shown and described.

DESCRIPTION

FIG. 1 is a perspective view of a dispenser;
FIG. 2 is a front elevation view of the dispenser shown in FIG. 1;

FIG. 3 is a rear elevation view of the dispenser shown in FIG. 1;

FIG. 4 is a top plan view of the dispenser shown in FIG. 1;
FIG. 5 is a bottom plan view of the dispenser shown in FIG. 1;

FIG. 6 is left-side elevation view of the dispenser shown in FIG. 1; and,

FIG. 7 is right-side elevation view of the dispenser shown in FIG. 1.

The portions shown in broken line form no part of the claimed design.

The bold, wavy lines do not constitute a feature of the design and they are included for illustrative purposes only to define the boundary of the claimed design.

1 Claim, 6 Drawing Sheets
